UNITED STATES PATENT OFFICE.

HAROLD ROWNTREE, OF CHICAGO, ILLINOIS, ASSIGNOR TO NATIONAL PNEUMATIC COMPANY, OF CHICAGO, ILLINOIS, A CORPORATION OF WEST VIRGINIA.

DOOR-OPERATING MECHANISM.

1,172,561.

Specification of Letters Patent.

Patented Feb. 22, 1916.

Application filed July 1, 1910. Serial No. 569,843.

To all whom it may concern:

Be it known that I, HAROLD ROWNTREE, a citizen of the United States, residing at Chicago, county of Cook, State of Illinois, have made a certain new and useful Invention 5 in Door-Operating Mechanism, of which the following is a specification.

This invention relates to door operating mechanism, and particularly to folding doors, or doors composed of foldable panels, and means for operating the same.

The object of the invention is to provide a construction of foldable door and means for operating the same, which is simple and 15 efficient in operation.

A further object is to provide a construction of door and operating means therefor wherein the door is made in hinged or pivoted panels which are foldable together 20 in opening, and distended into line with each other in closing.

A further object is to provide a car with doors of foldable sections with means controllable from a convenient point within the 25 car for operating the door.

Other objects of the invention will appear more fully hereinafter.

The invention consists substantially in the construction, combination, location and 30 relative arrangement of parts, all as will be more fully hereinafter set forth, as shown in the accompanying drawings, and finally pointed out in the appended claim.

In the accompanying drawings, Figure 1 35 is a view in side elevation, of a foldable door showing a form of operating mechanism therefor, and embodying the principles of my invention, the upper part of the door sections being broken off. Fig. 2, is a 40 top plan showing the door panels occupying closed position and one form of connecting mechanism therefor for folding the panels upon each other in opening. Fig. 3 is a view similar to Fig. 2, showing the panels 45 of one door in folded position to open the doorway. Fig. 4 is a view similar to Figs. 2 and 3, showing another form of connecting mechanism for the door panels, and embraced within the scope of my invention. 50 Fig. 5 is a view in side elevation of the construction shown in Fig. 4. Fig. 6 is a view in section, taken transversely of a street or

other car, showing a form and arrangement of manual operating means adapted for use in connection with my invention.

55

The same part is designated by the same reference sign wherever it occurs throughout the several views.

In carrying out my invention I employ 60 a door composed of panels or sections suitably hinged or otherwise connected together for relative swinging or other movement, whereby, in opening the door panels fold upon each other and in closing they are distended into aligned relation, and I provide 65 suitable connecting mechanism intermediate the door panels or sections, whereby the enforced movement of one section which may be called the primary or master section for description purposes, will cause the proper 70 movements of the other sections or panels into their opened or closed position as the case may be. The enforced movement of the primary or master section or panel of the door may be accomplished manually or 75 by power mechanism as may be desired, and may be controlled from any suitable or desired point within the contemplation of my invention.

In the practical application of my invention, and particularly where the apparatus is employed on a street railway, elevator, or other car, I prefer to so arrange the door panels or sections, and their connecting and operating mechanism that, in opening, the 80 central panel or panels, that is, the ones occupying the central portion of the doorway when closed, will move outwardly 85 thereby permitting occupants of the car to stand or remain in close proximity to the 90 door without interfering with the proper operation thereof.

In the accompanying drawings I have shown various constructions, forms and arrangements embodying the principles of my 95 invention, which I will now proceed to describe more in detail.

Referring to Figs. 1, 2 and 3, I have shown my invention as embodied in a double folding door, each composed of suitably hinged or relatively movable panels or sections as above indicated, one foldable door being arranged on one side of the doorway and the other on the other side of the 100

doorway, the two coöperating together to open and close the doorway when properly operated. My invention, however, as defined in the claim, is not to be limited or restricted to a double folding door construction. In these views of the drawings reference signs 1, 1, designate what for descriptive purposes, I shall refer to as the primary or master sections or panels of the two halves respectively of the double door. These panels or sections are respectively secured at one edge, to the shafts 2, 2, vertically journaled adjacent the door jambs, whereby, by rotating said shafts these primary or master door sections or panels will be rocked or moved about the axes of said shafts. The panels or sections 3, 3, of the door are respectively hinged or otherwise suitably connected concentric with the axis 20 of gears 18, as indicated at 90 for relative movement to the outer edges of the primary sections 1, 1. The shafts 2, 2, are geared to a rock shaft 6, suitably and conveniently journaled, whereby, by rocking the shaft 6, a coincident rocking movement of shafts 2 in unison with each other is secured. A single bevel gear arrangement 4, 5, is shown for connecting the shafts 2 and 6.

I will now describe one form of means for connecting the panels or sections of the door so as to secure a coincident operation thereof in unison when the primary or master panels are moved. Mounted concentrically with the shafts 2, but secured rigidly against rotative movement therewith, is a gear wheel 17, see Figs. 2 and 3. A gear wheel 18, preferably of one half the diameter of gear wheel 17, is secured rigidly to the hinged edge of door panel 3, being arranged in axial line with the hinge of said panel, as indicated at 90 and preferably secured to the hinge axis or pin thereof. An intermediate gear 19 mounted on a bearing pin on the upper end surface of the panel 1, intermeshes with the gears 17, 18. From this arrangement of gearing connections it will be readily seen that when either of the shafts 2 is given an axial rotative movement through an arc of ninety degrees, that is, is given a one quarter revolution, the primary door panel 1, associated therewith is brought into the position shown in Fig. 3, while, at the same time, the door panel 3, is, through the connecting gearing above described, folded upon the section or panel 1, as shown in Fig. 3, the hinged edge thereof moving in one direction through an arc of ninety degrees and the outer or free edge of such panel moving in the opposite direction through a similar arc, thereby securing an opening of the door way by reason of the door sections or panels folding upon each other by a combined swinging and sliding movement against the sides of the doorway.

Where a double door is employed it is evi-

dent that each half will be similarly operated and in unison, the sections of one half folding by a combined sliding and swinging movement upon each other and upon one side or jamb of the doorway and the sections of the other half similarly folding upon each other and upon the other side of jamb of the doorway.

It is obvious that many other forms of connections between the door panels may be employed, and each door may be composed of more than two panels, without departure from the spirit and scope of my invention.

In Figs. 4 and 5, I have shown a door composed of three panels or sections, 51, 54, 55 though in this respect I do not desire to be limited or restricted, and instead of intermeshing gears I employ sprocket chains operating around gear wheels. Thus one gear wheel 50, is stationary and has the same arrangement and relation with respect to the shaft 2 and the primary door panel or section 51, as the gear wheel 17, above described. The pivot pin 52, of the panel 54, carries pivotally mounted thereon two gears 53, 56, one of which is secured to panel 54, the other, which is secured to panel 51. The pivot pin 57, of panel 55, carries one gear 58, which is secured to panel 55. The gears 56, and 58, are of the same diameter, and the gear 50 is twice the diameter of gear 53. A sprocket chain 59, operates over the gears 50 and 53, while a sprocket chain 60, operates over gears 56 and 58. In this manner it will be obvious that as many door panels or sections as desired may be employed, and that when the shaft 2, is rocked, as above explained, the several sections or panels of the door will fold upon each other and upon the side of the doorway, in opening, or will be distended into alignment with each other in closing.

The construction of folding doors as heretofore employed have been open to the objections that when moved to complete open position, that is, when the panels are in parallel position, it requires a complicated arrangement of lever mechanism to operate them and the door is caused to open inwardly. This is objectionable in the case of street or other cars for the reason that with the door opening in this manner passengers or occupants of the car, if standing close to the door are liable to interfere with the operation of the door or else to be injured. In an arrangement embodying my invention, however, I am enabled not only to avoid the necessity for the use of complicated lever connections, but also to cause the central door panels to move outwardly in opening, thereby enabling occupants or passengers of the car to stand in close proximity to the doorway without interfering with the proper operation of the door.

It may sometimes be desirable to employ a foldable or movable step and to associate the same with the door operating mechanism so that when the door panels are 5 folded upon each other or moved into open position the step will move automatically and coincidentally into position for use, and when the door sections or panels are distended into closed position the step will be 10 automatically and coincidentally moved into retracted position. This coincident and coöperative movement of the door and step may be accomplished in a wide variety of ways. In Figs. 1 and 6, I have shown a 15 simple and efficient arrangement for accomplishing the desired object where I connect a step 7, through brackets 8, or otherwise, rigidly to the shaft 6, whereby when said shaft is rocked to operate the door sections or panels, the step is coincidentally operated. A limit stop 22 connected to the bracket which carries the step and arranged to bring up against the shaft 2, or other convenient part may serve to give a rigid 25 support for the step when in position for use.

As above indicated the doors, or the door and step, where a step is employed, may be operated in any convenient manner, 30 manually, or by power mechanism, or otherwise, as may be desired, and from any suitable or convenient point. In Fig. 1, I have shown one form of power mechanism for this purpose, and comprising a power cylinder 61, controlled by a valve mechanism arranged in casing 16, and operated in any suitable manner, as for instance by a control handle 62, and intermediate link connections 63, 64 and 15. A rocking gear 65, 35 operated by the motor 61, has an arm 13, connected by a link 12 to one arm of a bell crank lever 11, the other arm of said bell crank lever being connected by rod 10, with a crank arm 9 on the rock shaft 6. The 40 power mechanism above described may be of any desired construction and arrangement and capable of securing a cushioning effect, as more fully shown, described and claimed in my Patent No. 870,051, granted 45 Nov. 5, 1907, and pending application Serial No. 393,911, filed Sept. 21, 1907, and in the pending application of Paris R. For- man, Serial No. 393,908, filed Sept. 21, 1907.

In Fig. 6 I have shown a construction of 50 manually operated mechanism which is well adapted for use in connection with my invention, and embraced within the scope thereof, and wherein a hand lever 23, is placed in convenient position, preferably at 55 a point within the car, and intermediate the transverse width thereof, and, if desired, near or adjacent a convenient point to be within easy reach of the conductor, either when occupying a position where he 60 collects the fares of the passengers or at

any desired or convenient location. This hand lever is connected to a rock shaft 24, which, if desired, may extend up through the floor of the car and through a post 25, or otherwise, as may be convenient or desired. Upon the lower end of shaft 24, is mounted a gear wheel 26, meshing with and actuating another gear wheel 27, having eccentrically connected thereto one end of a rod 28, the other end of said rod being connected to the crank arm 9 on shaft 6. The shaft 24, may be prevented from rotating too far in any suitable or convenient manner, as, for instance, by means of stops 29, carried by gear 26, and adapted to strike 70 against the bracket 30, in which shaft 24, is journaled, or against any other suitable or convenient point.

It may be desirable to prevent the doors or door panels from being forcibly moved 75 out of their completely closed position by pressure applied thereto, as, for instance by passengers in a car pressing thereagainst. This may be accomplished in many specifically different ways. I have 80 shown a simple and efficient construction for the purpose, wherein I provide the door panels 3, at a convenient point on their outer or free edges for instance, on the upper end surfaces of the panels near their 85 outer vertical edges, with lugs or shoes 20, adapted, when the door panels or sections are in their completely closed position to enter between the guide plates 21, station- 90 arily mounted on the lintel or framework 95 above the doorway. It is obvious that many other specific structures might well subserve the same purpose. By the provision of such means it will be readily seen that the gear connections between the various panels are 100 relieved of strain in case the door panels 105 are pressed against.

It may also be desirable to provide means for automatically locking the door panels in 110 their completely closed position. This may be accomplished in many specifically different ways. For instance, in the case of the use of power mechanism for operating the apparatus the lever connections intermediate the motor and the shaft 6, may be ar- 115 ranged at some convenient point to pass a dead center as the door panels attain completely closed position. In the form shown the link or rod 12 may be employed and ar- 120 ranged in this manner to accomplish the de- sired result. Similarly the doors may be locked in their completely opened position. In the case of the manually operated devices shown in Fig. 6, the same results may be 125 attained by so proportioning the gears 26, 27, that the latter will rotate slightly beyond a half revolution while the door moves from one limit of its movement thereby causing the rod 28 to assume dead center positions and hence locking the doors opened or closed 130

as the case may be while the handle 23 and gear 26 can be given any desired relative degree of movement.

The principles of my invention may be embodied in many other different constructions and arrangements and still fall within the scope of my invention. While, therefore, I have shown and described various specific constructions and embodiments in 10 the broadest scope of my invention as defined in the claim I do not desire to be limited or restricted to such specific constructions.

It is obvious that my invention is well 15 adapted for use in any relation or situation where hinged or foldable doors or hinged or foldable doors and steps associated together are employed, as in street or other railway cars, elevators, houses or other 20 buildings, or the like. I do not desire therefore, to be limited in respect of the location or place of use of the apparatus. And while a construction embodying the principles of my invention is adapted for use 25 generally, it is particularly desirable in connection with the doors of street or other cars especially for the doors in the sides of the car since I avoid the necessity for providing pockets in the sides of the car to receive the 30 doors when open and since the doors are not required to slide in a right line they may be applied to the rounding or slightly tapering contour of the car platforms at the ends 35 of the cars, and hence may be applied to cars already built, and not requiring a special construction of car body.

I do not claim herein the combination

which includes the step as the same forms the subject matter of my application Serial No. 476,031, filed February 4, 1909.

40

Having now set forth the object and nature of my invention, and various constructions embodying the principles thereof, and having explained such constructions, their purposes, functions, and modes of 45 operation, what I claim as new and useful, and of my own invention and desire to secure by Letters Patent is:

A door including a primary and a secondary panel, a vertical rock shaft arranged 50 at the side of the doorway and to which the outer edge of the primary panel is connected, the outer edge of the secondary panel being hinged to the inner edge of the primary panel, connections intermediate the adjacent edges of said panels, whereby when one is rocked the other is coincidentally rocked in the opposite direction, and means for rocking said shaft, the construction including automatic means for locking said 55 panels at the limits of their movements, and means arranged to engage the inner edge of the secondary panel when the panels are extended into line with each other to prevent movement thereof independently of the vertical shaft rocking means.

In testimony wherof I have hereunto set my hand in the presence of the subscribing witnesses, on this 9th day of June A. D., 1910.

HAROLD ROWNTREE.
